Letters Patent No. 22 dated July 19th 1844

The Schedule referred to in this Letters Patent and
making part of the same. —

To all whom it may concern, —

Be it known that A. Mayziah Whitney of the
City & County of Albany & State of New York have invent-
ed or produced, new designs or ornaments to be cast or stamped
upon iron or other plates, used in the construction of stoves,
and I do hereby declare that the following is a full &
exact description of the same, reference being had to the
 annexed drawings.

Fig. 1, represents a stove composed in part of the
plates a, b, c, d & e, which are further represented in detail
in the elevations a', b', c', d' & e' which last is the part of
the design or ornaments of which I claim to be original.
The designs or ornaments which I claim to original & my
invention are designated on said elevations, by a", b", c",
d", & on e" by e".

That I claim as my invention and design
to secure, by letters patent are the designs, ornaments
& configurations, as represented, within the red lines,
upon the annexed drawings, to be cast, or stamped up-
on iron or other plates, used in the construction of
stoves. I do not claim the form or arrangement of
the stove, nor anything connected, with it other than
the designs, ornaments or configurations represented
within the red lines upon the annexed drawings.
